FLUID MOTOR

Max Kraut, La Libertad, Chontales, Nicaragua,
assignor to Southwestern Engineering Company,
Los Angeles, Calif., a corporation of California

Application November 7, 1941, Serial No. 418,156

13 Claims.

(Cl. 121—164)

This invention relates broadly to fluid motors and more particularly to a fluid driven apparatus for producing reciprocation of a member normally subject to a force acting in one direction. Such motors are particularly useful in operating jigs for the recovery of minerals, such for example as the improved jigs shown in my co-pending applications Serial No. 228,518, filed September 6, 1938, now Patent No. 2,271,650, issued February 3, 1942, and Serial No. 319,613, filed February 19, 1940, of which this present application is a continuation in part.

As disclosed in said co-pending applications, a jig is broadly an apparatus comprising a permeable bed, preferably composed of sand and other particles, supported by a screen, over which flows a mixture of water, gangue, and the mineral desired to be recovered, there being means to provide an intermittent upward flow of water through the bed, resulting in a classifying action therein by which the relatively heavy mineral desired to be recovered passes through the bed into a hutch below, while the gangue passes over the bed and out of the apparatus.

The major object of my invention is to provide simple and efficient actuating means which is capable of imparting a rapid reciprocating motion to a jig or other device desired to be reciprocated, which motion is of such nature that the velocities during upward and downward strokes may be kept approximately constant over approximately the entire strokes, and the velocity during the downward stroke can be much greater than the velocity during the upward stroke.

Another object of my invention is to provide fluid-operated means for obtaining the above type of motion.

Another object is to provide in a fluid-driven reciprocating means, a resilient valve disc which is so constructed as to reduce the tendency for it to pass out through the outlet which it closes.

A further object is to provide a water motor having means for allowing escape of air released from the water used in driving the motor.

These and other objects and advantages will become apparent from the following description of different embodiments of my invention and from the accompanying drawings in which:

Fig. 1 is an elevational view, partly in section, showing one embodiment of my invention, the controlling valve member being shown in the position in which it is undeflected.

Fig. 2 is a horizontal sectional view of the apparatus of Fig. 1, taken along the line 2—2,

Fig. 3 is a diagrammatic view showing the controlling valve in its uppermost position,

Fig. 4 is a view similar to Fig. 3, but showing the valve in its lowermost position.

Fig. 5 is a vertical sectional view of a modified form of fluid motor embodying my invention, the controlling valve member being shown in the position in which it is undeflected.

Fig. 6 is an enlarged sectional view of the bellows forming a part of the motor shown in Fig. 5.

Fig. 7 is a partial sectional view of the fluid motor of Fig. 5, showing the controlling valve in its lowermost position.

Fig. 8 is a view similar to Fig. 7, but with the valve in its uppermost position, and

Fig. 9 is a diagram illustrating the manner of variation of displacement of the moving parts of my fluid motors with time.

Referring now to the drawings, and particularly to Figs. 1—4 thereof, the numeral 10 designates a vertical shaft or rod adapted to be attached to the body to be reciprocated, in the case of a jig, this being the collecting pan. Under normal conditions, the rod 10 will tend to move downwardly in response to the gravitational pull thereon. The rod 10 is movably mounted, and is adapted to be reciprocated in a vertical path as will now be described.

An outer cylindrical housing 11 is secured to a bridge-like structure 12 adapted to span a jig or other apparatus from side to side in convenient manner. Within the housing 11 is located a cylinder 13 attached to the housing 11 at circumferentially spaced locations and opening at top and bottom into the housing 11. A water supply pipe 34 is screwed into the housing 11 and cylinder 13 and feeds water under pressure directly into the cylinder 13. The cylinder 13 at its lower end is conical in shape and serves as a valve seat 14 for a circular valve disc 15 of resilient material, such for example as rubber, which is preferably of tapering cross-section, facilitating flexing of the disc. A piston 16 closely fitting the cylinder 13 is adapted to move therein above the water inlet pipe 34. The piston 16 and valve member 15 are mounted on an axial tube 17, being pressed against the shoulder 18 by the tightening of nut 19. The valve disc 15 has an area less than that of the piston 16 and is mounted so as to be unsupported in its peripheral portion. The tube 17 extends upwardly through a bearing 20 mounted in a cover 21 secured to the top of housing 11 by bolts 22. A lubricating fitting 23 is connected through the cover 21 to conduct lubricant to the bearing 20.

A diaphragm 24, preferably of rubber or canvas, and apertured to permit tube 17 to pass therethrough, is clamped between housing 11 and cover 21 to protect the bearing 20 from splash of water. The rod 10 passes through the tube 17, has a shoulder abutting the lower end of tube 17, and carries a nut 25 in threaded engagement therewith at its upper end which securely clamps the tube 17 and associated parts on the rod 10 for movement therewith. A spring 26 surrounds the tube 17, bears at one end on the cover 21 and at the other end against a washer 27 retained in an adjustable position by nut 28 in threaded engagement with tube 17. The spring 26 acts to balance part of the load on rod 10 due to the weight of the rod 10 and its associated parts, whereby the pressure and amount of fluid required to operate the reciprocating means is reduced. It should be noted that the spring 26 should never be made so strong as to completely balance all the load on rod 10, for then auxiliary means would have to be supplied to return the valve to the closed position.

Attached to the housing 11 at its lower end and in communication with the space within the housing 11 and cylinder 13 is a fitting 29 having a side outlet pipe 30 connected thereto and a pipe 31 connected to the bottom, surrounding rod 10, there being space left between the rod 10 and pipe 31. The pipe 31 may pass downwardly through the bed of the jig and into the hutch, if the motor is being used to operate a jig.

In the bottom of fitting 29 is preferably located a washer 32, preferably of rubber, clamped between a shoulder of the fitting and a nut 33 in threaded engagement with the fitting. The washer 32 may pack the rod 10 in contact therewith to prevent passage of any fluid into the pipe 31 or it may be of any suitable internal diameter to permit passage of any desired proportion of the available fluid past the washer, through the pipe 31 and into the hutch.

In the operation of this form of my actuating means to reciprocate the rod 10, liquid, preferably water, under pressure enters cylinder 13 through pipe 34 and acts upon both piston 16 and disc 15, the force on piston 16 in an upward direction being greater than the downwardly directed force on the valve member 15 by reason of the greater area of piston 16. The piston 16 therefore moves upwardly. If the disc 15 were inflexible it would also move upwardly coincidentally with piston 16; but being flexible, the periphery of disc 15 is held down in contact with the conical seat 14 while the center of the disc connected to piston 16 rises with the piston, as shown in Fig. 3. The piston 16 continues to rise until a critical point is reached where the periphery of the disc 15 can no longer be held in contact with the seat 14 by the water pressure, and the disc 15 then breaks from the seat. The valve disc snaps open quickly as the pressure on opposite sides of it quickly equalizes. At the same time the piston 16 moves farther up in the cylinder due to the momentum it has acquired. Thus the opening closed by disc 15 is rapidly opened, resulting in an instantaneous drop in pressure, which, among other things, depends upon the restriction of a valve, (not shown), in supply pipe 34. The sudden drop in pressure within the cylinder 13 together with the reduced pressure underneath disc 15 due to the high velocity of water passing through the narrow opening between the seat 14 and the disc 15 causes

the piston 16 to be pulled rapidly downward by the weight of rod 10 and its associated parts. As soon as the piston and valve structure has fallen to a point where disc 15 contacts seat 14, pressure starts to build up again in cylinder 13. Since, however, the disc 15 is flexible, it can be distorted into the shape shown in Fig. 4 in which condition the volume within the cylinder between piston 16 and valve disc 15 is greater than in the condition illustrated in Fig. 1. It will be obvious that pressure cannot build up to a normal value within the cylinder so long as this volume is increasing. For this reason, the piston 16 and valve disc 15 sink to a lowermost position illustrated in Fig. 4. The pressure within the cylinder then builds up quickly and causes the piston 16 to be raised while the periphery of the disc 15 is held in contact with seat 14, the piston and disc going through the position shown in Fig. 1 and on through the remainder of the cycle as previously described. Since any momentum possessed by the moving parts at the time of unseating of the valve disc 15 is quickly overcome by the unbalanced force of gravity, there is very little upward movement after this time, and nearly all of the upward stroke of the member 10 takes place while the valve disc 15 is seated on the seat 14.

The water discharged from the cylinder past the disc 15 when in the open position passes into the fitting 29 and out through pipe 30, a portion thereof, depending upon the opening between washer 32 and rod 10, passing down the pipe 31 to supply make-up water to the jig hutch. Any water leaking past the piston 16 enters the space between housing 11 and cylinder 13 and runs down to join the discharge water in fitting 29. The diaphragm shield 24 prevents any of this water from splashing up into the bearing 20.

The resulting reciprocation of rod 10 is very rapid and regular. The number of strokes per minute may be adjusted by varying the diameter of the disc 15 or by varying the restriction of the water supply. In one embodiment of this form of my device, about 200 complete cycles per minute were obtainable with a disc 5 inches in diameter, and with a disc 4 inches in diameter the number of cycles could be adjusted from 400 to 1000 per minute, finally reaching a vibratory movement. The extent of the movement depends upon the diameter of the disc 15, greater movement being obtained, within limits, by use of a disc of a larger diameter. In the device above referred to, a movement of 1½ inches was obtained by use of a disc 5 inches in diameter, while a movement of ¼ inch was obtained by use of a disc of 4 inches in diameter.

The movement of the piston 16 is relatively slow on its upward stroke because a relatively large weight is being lifted by the water pressure acting only on the differential area of piston 16 and disc 15, while on the downward stroke the weight connected with rod 10 pulls the piston down very rapidly against a greatly reduced pressure. It is found by actual test that both the upward and downward velocities of the member 10 and associated parts are approximately constant over approximately the entire stroke thereof. This type of reciprocation involving a rapid downward stroke of constant velocity and a relatively slow upward stroke of constant velocity has been found to be particularly well adapted to operation of a jig, resulting in more efficient recovery than with reciprocation of equal velocity on the two oppositely directed strokes. It is to be understood, of course, that

the reciprocating means herein disclosed may be advantageously employed in jigs of various constructions and may also be used for purposes other than reciprocation of a jig.

Referring now to Figs. 5 to 8, wherein is illustrated a modified form of fluid motor actuating means embodying my invention, the numeral 11 again indicates a housing which may be secured to a bridge-like structure 12 spanning a jig from side to side or attached to other means to be operated. The housing 11 is at its lower end preferably conical in shape and serves as a valve seat 14 for a resilient valve disc 48, preferably of rubber, which is connected for movement with the rod 10. The valve disc 48 may be clamped between a shoulder on the sleeve member 17 and a nut 19, and the sleeve member 17 may be held against a shoulder on the rod 10 by means of a sleeve member 52 on the rod 10 and a nut 25 threaded on the upper end of the rod 10.

The valve member 48 in this form of my invention is preferably of tapered cross-section, being thin near the center support to provide flexibility, and thickest at the peripheral edge to prevent the valve member from passing through the outlet 54 from the housing. I find that when I use a valve member 48 having a thick edge, as shown, it is possible to considerably increase the size of the outlet 54 over that which is possible when using a relatively thin-edged valve member such as that previously described herein, and still keep the valve member from passing through the outlet on the downward stroke. It will be evident why this is so from an inspection of Fig. 7 in which the valve member is shown in its lowermost position. It will be observed that in this position the lower peripheral edge of the valve member is forced even farther out radially than when the valve member is undeflected. Thus, a tendency of the valve member to pass through the outlet 54 on the downward stroke is averted.

A bellows 55 of flexible material, preferably rubber, and of diameter larger than the valve member 48, is housed within the housing 11, having its upper end clamped between the housing 11 and a cover 21 and its lower end attached to a plate 51 clamped between the sleeves 17 and 52. The bottom of the bellows thus constitutes a movable wall of the fluid chamber, similar in effect to the movable wall piston 16 of Fig. 1. Within each of the outwardly extending folds of the bellows 55, for lateral reinforcement of the bellows, I preferably place a metal ring 58, and all of the rings 58 are preferably held in place by means of a plurality of strips 60 of flexible material, preferably rubber which are vulcanized or otherwise secured to the inside surface of the bellows so as to cover over the rings 58 at locations circumferentially spaced around the bellows. A hole 61 is located in the cover 21 to permit air to freely move into and out of the space within the bellows 55.

The sleeve 52 is slidably guided in a bearing 20 in the cover 21, and a compression spring 26 surrounds the sleeve 52 and at one end abuts the cover 21 and at the other end abuts a nut 28 threaded on the sleeve 52. The spring 26 acts to balance part of the load due to the weight of the parts supported by rod 10.

A water inlet pipe 34, provided with a control valve not shown, discharges into the chamber formed within the housing 11 at a point between the valve member 48 and the bellows 55. To the outlet end of the housing 11 below the outlet

54 is connected a fitting 29 having a side discharge pipe 30 connected thereto and a pipe 31 connected to the bottom thereof and surrounding the rod 10. Space is left within the pipe 31 around the rod 10 for the passage of water. The pipe 31 may pass downwardly through the bed of a jig and open into the hutch thereof when my device is being used in connection therewith. In the bottom of the fitting 29 is located a washer 32, preferably of rubber, clamped between a shoulder of the fitting and a nut 33 in threaded engagement with the fitting. The washer 32 may pack the rod 10 in contact therewith to prevent passage of any fluid into the pipe 31 or it may be of any suitable internal diameter to permit passage of any desired proportion of the available water past the washer, and through the pipe 31.

20 I have found that water which is passed through the motor generally contains air which is to some extent released within the housing 11 and accumulates in the uppermost portion of the space accessible to fluid between the bellows 55 and the housing 11, seriously hampering the action of the motor. It is found that a longer and more regular stroke is obtained if air is prevented from accumulating in this region and I consequently provide a pipe 75 in communication with the interior of the housing 11 adjacent the uppermost portion of the fluid chamber between the bellows 55 and the housing 11, the pipe 75 extending upwardly beyond the highest point of the fluid chamber and preferably including a control valve 76 located at the highest elevation of the pipe 75. The valve 76 may then be set so as to continuously pass a small stream of water which effectively sweeps air out of the fluid chamber of the motor and prevents its accumulation therein.

40 In the operation of this form of my fluid motor to reciprocate the rod 10, a fluid, preferably water, under pressure enters through the pipe 34 and acts upon both the valve member 48 and the movable wall comprising the plate 51 and the under side of the bellows 55, the force on the latter being greater than that on the valve member 48 by reason of the greater area acted upon. The rod 10 is, therefore, moved upwardly. Since the valve member 48 is flexible, the periphery thereof continues to be held down against its seat by water pressure while the rod 10 moves upwardly. The rod 10 continues to move upwardly until the valve member 48 is deflected to such an extent that the water pressure on it can no longer hold its periphery on the seat 14. The conditions existing at this moment may be as illustrated in Fig. 8. Following a slight additional upward movement of the rod 10, the periphery of the valve member 48 will snap upwardly by reason of its resilience and open a passage to the outlet 54. Water then immediately rushes out of the outlet 54 and there is an instantaneous drop of the pressure beneath the bellows 55. The heavy weight of the rod 10 and its associated parts causes the rod 10 to drop rapidly. When it has fallen to a point where the valve member 48 contacts the seat 14, pressure starts to build up again in the fluid chamber, but because of the momentum of the moving parts, they fall to a point where the conditions may be as illustrated in Fig. 7. At this point fluid pressure has overcome the downward movement and starts to move the bellows 55 and rod 10 upward, the motor again going through the cycle described above. The reciprocation of

the rod 10 may be made slow or rapid as desired by control of the valve on pipe 34.

It is important to note that in the action of the fluid motors of my invention, any substantial movement of the movable wall comprising the piston 16 of Fig. 1 or the plate 57 and the bottom of the bellows of Fig. 5 results in a corresponding movement of the rod 10, and that the valve member 15 or 48, as the case may be, is sufficiently flexible so that while the valve member is still closing the outlet the rod 10 is permitted to move through nearly its full stroke in the upward direction.

The water which is discharged from the motor passes into the fitting 29 and out through the pipe 30, a portion thereof, depending upon the opening between the washer 32 and the rod 10, passing down the pipe 31 to supply make-up water to the hutch.

The type of reciprocation resulting from the operation of the motors herein described is diagrammatically illustrated in Fig. 9 and is characterized by relatively slow upward strokes AB, CD, EF, etc., during which the displacement varies substantially uniformly with time, and relatively rapid downward strokes BC, DE, FG, etc., during which the displacement varies substantially uniformly with time. Thus, both the upward and downward velocities of the rod 10 and the water in the hutch of the jig are approximately constant over approximately the entire stroke, while the downward velocity is much greater than the upward velocity. The importance and value of these velocity conditions is evident from the following analysis.

In order to maintain the permeable bed of a jig in a state of suspension and to secure the greatest amount of work from the jig per unit of time, it is desirable to move the water upwardly and downwardly through the bed with a relatively large number of alternations of movement per unit of time. But to permit high recovery of fine concentrate particles, it is desirable to employ not too great an upward velocity of water. The most efficient condition, therefore, is one in which the downward velocity of water is considerably greater than the upward velocity of the water, for by this means the upward velocity may be limited to an efficient value and the number of strokes per unit of time may be maintained large. If, however, the downward velocity is too great at any time, the bed tends to pack too severely, so it is clear that with a given maximum amount of water desired to be moved downwardly and a definite limit placed upon the maximum instantaneous downward velocity, the most efficient condition will be that in which the downward velocity is approximately constant over approximately the entire period of downward movement. By this means a sufficiently rapid alternation of movement is secured to maintain the bed in an efficient condition and it is prevented from packing severely on the downward stroke. It will also be evident that the most efficient condition during the upward stroke is one in which the velocity is approximately constant over approximately the entire stroke because for any other condition during those periods when the velocity is higher than the most suitable velocity, proper recovery of fine concentrate particles is being hampered, while during those periods when the velocity is less than the permissible value, time is simply being wasted and could better be employed

in increasing the number of alternations per unit of time.

From the foregoing it will be seen that both of the embodiments of my invention herein described are capable of attaining the objects and accomplishing the advantages hereinbefore set forth, and it is to be understood that I do not mean to be limited to any of the specific showings herein except as limited by the claims appended hereto.

I claim as my invention:

1. Apparatus for producing reciprocation of a member normally subject to a force acting in one direction, which includes: a cylinder having an outlet at one end; a piston movable in said cylinder and connected to said member in such manner that movement of said piston results in a corresponding movement of said member; a flexible valve disc of area less than that of said piston and connected to said member, said valve disc being adapted to close said outlet upon movement in response to said normally acting force and being sufficiently flexible to permit material movement of said member while still closing said outlet; and fluid supply means connected with the interior of said cylinder between said piston and said valve disc.

2. Apparatus for producing vertical reciprocation of a member urged downwardly by the force of gravity on said member and its associated parts, which includes: a spring acting to partially balance said force of gravity; a cylinder having an outlet at the lower end; a piston movable in said cylinder and connected to said member in such a manner that any substantial movement of said piston results in a corresponding movement of said member; a flexible valve disc of area less than that of said piston and connected to said member, said valve disc being adapted to close said outlet upon downward movement and being sufficiently flexible to permit material movement of said member while still closing said outlet; and fluid supply means connected with the interior of said cylinder between said piston and said valve disc.

3. Apparatus for producing reciprocation of a member normally subject to a force acting in one direction, which includes: a cylinder having an opening at one end and a conical surface adjacent said opening; a piston movable in said cylinder and connected to said member in such manner that movement of said piston results in corresponding movement of said member; a flexible valve disc of area less than that of said piston and connected at its center to said member, said valve disc being adapted to engage said conical surface to close said opening upon movement in response to said normally acting force and being sufficiently flexible to permit material movement of said member while still closing said outlet; and means for supplying fluid under pressure to the interior of said cylinder between said piston and said valve disc.

4. Apparatus for producing vertical reciprocation of a member urged downwardly by the force of gravity on said member and its associated parts, which includes: a spring compressed between said member and a stationary part of said apparatus acting to partially balance said force of gravity; means for changing the force exerted by said spring; a stationary housing; a cylinder contained within said housing and supported thereby at circumferentially spaced locations, said cylinder having an opening at its lower end and conical surface adjacent said opening;

a piston movable in said cylinder and connected to said member in such manner that movement of said piston results in movement of said member; a flexible valve disc of area less than that of said piston and connected at its center to said member, said valve disc being adapted to engage said conical surface to close said opening upon downward movement; and means for supplying fluid under pressure to the interior of said cylinder between said piston and said valve disc.

5. Apparatus for producing vertical reciprocation of a member urged downwardly by the force of gravity on said member and its associated parts, which includes: a housing open at its lower end; a cylinder contained within said housing and supported thereby at circumferentially spaced locations, said cylinder having an opening at its lower end and a conical surface adjacent said opening; a piston movable in said cylinder and mounted concentrically on said member in such manner that any substantial movement of said piston results in corresponding movement of said member; a flexible valve disc of area less than that of said piston and mounted on said member so as to leave its peripheral portion unsupported, said valve disc being adapted to engage said conical surface to close said opening upon downward movement and being sufficiently flexible to permit material movement of said member while still closing said outlet; means for supplying fluid to the interior of said cylinder between said piston and said valve disc; a cover attached to the top of said housing through which said member extends; a bearing in said cover serving as a guide for said member; and a shield clamped between said housing and said cover positioned between the top of said cylinder and said bearing and apertured to permit said member to pass therethrough.

6. Reciprocating apparatus, which includes: walls forming a chamber provided with an inlet and an outlet for fluid, one of the walls of said chamber being movable; a reciprocable member connected to said movable wall in such manner that any substantial movement of said movable wall results in corresponding movement of said member; a valve element of area less than that of said movable wall and associated with said reciprocable member to normally close said outlet, said valve element being adapted to continue to close said outlet during initial movement of said reciprocable member in a direction corresponding to outward movement of said movable wall but to be unseated by continued movement of said reciprocable member to open said outlet.

7. Apparatus for producing reciprocation of a member normally subject to a force acting in one direction, which includes: walls forming a chamber provided with an inlet and an outlet for fluid, one of the walls of said chamber being movable and connected to said member in such manner that any substantial movement of said movable wall results in corresponding movement of said member, and a flexible valve disc of area less than that of said movable wall and connected to said member, said valve disc being adapted to close said outlet upon movement in response to said normally acting force and being sufficiently flexible to permit material movement of said member while still closing said outlet.

8. Apparatus for producing reciprocation of a

10 member normally subject to a force acting in one direction, which includes: walls forming a chamber having a fluid inlet and a fluid outlet, one of said walls being a movable wall positively connected to said member in such manner that an increase in the volume of fluid in said chamber causes a proportional movement of said member; and a flexible valve disc of area less than that of said movable wall connected to said member, said flexible valve disc being adapted to close said fluid outlet upon movement of said member in response to said normally acting force and having an unrestrained area capable of distortion to maintain said fluid outlet closed throughout substantially the entire stroke of said member caused by increase in the volume of fluid in said chamber.

15 9. Apparatus for producing reciprocation of a member normally subject to a force acting in one direction, which includes: a cylinder having an opening at one end and a conical surface adjacent said opening; a piston movable in said cylinder and positively connected to said member in such manner that an increase in the volume of fluid in said cylinder causes a proportional movement of said member; a flexible valve disc of area less than that of said piston and connected at its center to said member, said valve disc being adapted to engage said conical surface to close said opening upon movement in response to said normally acting force and having an unrestrained area capable of distortion to maintain said fluid outlet closed throughout substantially the entire stroke of said member caused by increase in the volume of fluid in said cylinder; and walls forming a passage for inlet of fluid into the interior of said cylinder between said piston and said valve disc.

20 10. Apparatus for producing vertical reciprocation of a member urged downwardly by the force of gravity on said member and its associated parts, which includes: a spring compressed between said member and a stationary part of said apparatus acting to partially balance said force of gravity; means for adjusting the force exerted by said spring; a stationary housing; a cylinder contained within said housing and supported thereby at circumferentially spaced locations, said cylinder having an opening at its lower end and a conical surface adjacent said opening; a piston movable in said cylinder and positively connected to said member in such manner that an increase in the volume of fluid in said cylinder causes a proportional movement of said member; a flexible valve disc of area less than that of said piston and connected at its center to said member, said valve disc being adapted to engage said conical surface to close said opening upon downward movement and having an unrestrained area capable of distortion to maintain said fluid outlet closed throughout substantially the entire stroke of said member caused by increase in the volume of fluid in said cylinder; and means for supplying fluid under pressure to the interior of said cylinder between said piston and said valve disc.

25 11. In a water-driven reciprocating means the combination of: a housing providing a water chamber within, a water inlet to said chamber on the side of said housing, and a water outlet at the bottom of said housing; a bellows secured at the top of said housing and extending into said chamber; a reciprocable member attached to the bottom of said bellows; a resilient valve member connected with said reciprocable member and

adapted to close said outlet upon downward movement of said reciprocable member, said valve member being of area less than that of the bottom of said bellows; and walls forming an outlet from said chamber located adjacent the highest point of said chamber for the escape of air released in said chamber.

12. In a water-driven reciprocating means the combination of: a housing providing a water chamber within, a water inlet to said chamber on the side of said housing, and a water outlet at the bottom of said housing; a bellows secured at the top of said housing and extending into said chamber; a reciprocable member attached to the bottom of said bellows; a resilient valve member connected with said reciprocable member and adapted to close said outlet upon downward movement of said reciprocable member, said valve member being of area less than that of the bottom of said bellows; a conduit in communication with said chamber adjacent the highest point

thereof and extending in an upward direction from said chamber; and a control valve in said conduit located at an elevation higher than any point of said chamber.

- 5 13. In a fluid-driven reciprocating means including walls forming a chamber provided with an inlet and an outlet for fluid, one of the walls of said chamber being movable, and a reciprocable member connected to said movable wall in such manner that any substantial movement of said movable wall results in corresponding movement of said member; a valve disc of resilient material of area less than that of said movable wall and connected to said member, said valve disc being adapted to close said outlet upon downward movement and being of tapered cross-section with the thickest unsupported portion of said valve disc being located at the periphery thereof.
